UNITED STATES PATENT OFFICE.

DANIEL H. SURGNOR, OF SHERMAN, TEXAS, ASSIGNOR TO ANNIE SURGNOR, OF SAME PLACE.

DESIGN FOR A HAME ATTACHMENT.

SPECIFICATION forming part of Design No. 30,730, dated May 9, 1899.

Application filed April 13, 1899. Serial No. 712,940. Term of patent 14 years.

To all whom it may concern:

Be it known that I, DANIEL H. SURGNOR, residing at Sherman, Texas, have invented and produced a new and original Design for Hame Attachments, of which the following is a specification, reference being had to the accompanying drawings.

In the drawings, Figure 1 shows the attachment in plan, while Fig. 2 is an elevation.

o The attachment is designed to be applied to the hames of a harness and to provide for the connection of the traces by means of a suitable hook.

The leading feature of the invention is in its symmetrical configuration, adapting it to be used for the right or left hand.

The attachment has a central ridge *a*, and from this ridge the sides recede to the base of the attachment, as shown at *b*, and in these receding sides are a series of holes *c*, the holes being in line with each other.

What I claim is—

The design for a hame attachment as herein shown and described.

In testimony whereof I affix my signature in presence of two witnesses.

DANIEL H. SURGNOR.

Witnesses:

R. H. HENRY,
T. L. BRAWE.
